(57) **CLAIM**

The ornamental design for a cell separation instrument, as shown and described.

DESCRIPTION

FIG. 1 is a front view of a cell separation instrument showing the new design;

FIG. 2 is a back view thereof;

FIG. 3 is a left view thereof;

FIG. 4 is a right view thereof;

FIG. 5 is a top view thereof; and

FIG. 6 is a bottom view thereof;

FIG. 7 is a perspective view thereof; and,

FIG. 8 is another perspective view thereof.

The broken lines show portions of the cell separation instrument that form no part of the claimed design.

1 Claim, 8 Drawing Sheets
